FRANK KESSLER, OF BROOKLYN, NEW YORK, ASSIGNOR TO THE LEO BAUM ESTATE, A.
RUSSELL BOND, EXECUTOR, OF NEW YORK, N. Y.

INTERCHANGEABLE JEWEL MOUNTING

Application filed May 31, 1929. Serial No. 367,370.

The present invention relates to jewelry and particularly to interchangeable jewel mountings, whereby different stones or ornaments may be readily applied to a piece of 5 jewelry and interchanged whenever desired.

An object of my invention is to provide a mounting in which a jewel may be securely held without requiring the manipulation of any screws or other fastening devices.

10 Another object of my invention is to provide a mounting in which a jewel is held by a pair of interengaging parts which are locked together by a spring latch.

A more specific object of my invention is to 15 provide a locket with a lid, the latter when in closed position cooperating with the locket to hold a jewel.

Other objects of my invention will appear 20 in the following description of a preferred embodiment and the novelty and scope of the invention will thereafter be pointed out in the claims.

In the accompanying drawing;

Figure 1 is a view in perspective of a locket 25 ring embodying my invention;

Fig. 2 is a similar view, but with the lid of the locket partly drawn out;

Fig. 3 is a sectional view of the ring, the section being taken in an axial plane, i. e. 30 on line 3—3 of Fig. 4;

Fig. 4 is a view of the ring in transverse section, the section being taken on the line 4—4 of Fig. 3; and

Fig. 5 is a bottom plan view of the lid of 35 the locket.

I have shown in the drawing, a ring 10 provided with an enlarged head 11 of rectangular form and having a recess 12 in the upper face thereof. This recessed head constitutes the 40 body of a locket. It will be understood, of course, that the locket portion of the ring may be either integral with the ring, as shown in the drawing, or, it may be made as a separate body soldered or otherwise secured to the ring proper.

The locket is provided with a lid 13 which has sliding engagement therewith. The side walls of the locket extend above the end walls to form lips 14 which are undercut to 50 overlap and slidably engage opposite edges of

the lid, said edges being preferably beveled to fit the undercut lips. The lid 13 consists of a rectangular plate formed at each end with upstanding lips 15 which are undercut or bent inward to overlap and slidably engage opposite ends of a jewel 16. The jewel is beveled at each end to fit snugly within the lips 15.

It will be observed that when the parts are assembled, as shown in Fig. 1, the jewel will 60 be held at each end by means of the lips 15 and will be confined at each side by the lips 14 of the locket body, so that it will be impossible for the jewel to be removed as long as the lid is closed, or, even partly closed 65 upon the body. However, when the lid is withdrawn from engagement with the body, the jewel may readily be slid laterally out of engagement with the lips 15.

To hold the lid in closed position, I provide 70 a spring latch which is secured to the lid 13 and has locking engagement with the locket body 11 when the lid is closed. This spring latch comprises a plate or clip 17, of spring metal, which is soldered or otherwise secured 75 to the bottom of the lid 13. The forward end of the clip 17 is free and is flexed away from the lid 13 and is provided at its extremity with a transverse plate 18. The plate 18 serves as a thumb piece for unlatching the 80 clip and is adapted to slide in the recesses 19 formed in the forward end wall or lip of the lid. The forward end wall 20 of the locket body is also provided with a recess 21 which is aligned with the recess 19 when the lid is 85 closed and serves to receive the lower portion of the plate 18. The upper edge of the wall 20 is also formed with a notch 22 adapted to receive the clip 17. The clip 17 is formed with a transverse groove 23, which is bordered on one side by the plate 18 and on the other by a shoulder 24.

When the lid 14 is closed, the spring clip 90 will snap over the wall 20 with the plate 18 bearing against the outer face of the wall and the shoulder 23 against the inner face of the wall. This will positively lock the lid against displacement. The outer face of the plate 18 lies flush with the outer face of the end wall 20 and also with the adjacent lip 100

15. The ring may be engraved with the joint between the plate 18 and the body and lid forming part of the design so as to conceal the presence of the clip.

5 The ring is assembled as follows: The jewel 16 is slid laterally into place on the lid 13 with the lips 15 engaging and holding opposite ends of the jewel. The lid is then slid into engagement with the body 11, and the lips 14 will not only hold the lid against lateral displacement, but will also overlap the side edges of the jewel so as to prevent the jewel from sliding out laterally. As the lid is slid home the spring clip 17 will snap over the notched portion 22 of the wall 20, and the shoulder 24 will prevent the lid from being accidentally drawn out, while the plate 18 will limit the extent to which the lid may be slid inward upon the body. At any time 10 that the user wishes to change the jewel, all he needs to do is to lift the plate 18 sufficiently over the shoulder 24 to clear the wall 20, and at the same time to draw the lid outward. After the lid has been withdrawn from the 15 locket, the jewel 16 may be removed and another jewel inserted in the lid in place of it.

It will be understood that my invention is not limited to the exact details of construction here illustrated and that I am at liberty to make such changes in form, construction and arrangement of parts as fall within the spirit and scope of the claims. It will be understood also that my invention is applicable not only to a locket ring but to rings not provided with locket bodies, and furthermore it may be applied to lockets not forming a part of a ring, as well as to other classes of jewelry.

20 40 Having thus described my invention what I claim as new and desire to secure by Letters Patent is as follows:

1. A locket comprising a body portion, a lid therefor, means on the lid for engaging a jewel at opposite edges thereof, and means integral with the body portion for overlapping intermediate edges of the jewel when the body portion is closed by the lid.

2. A locket comprising a body portion, a lid therefor, means on the lid for engaging a jewel at opposite edges thereof, means integral with the body portion for overlapping intermediate edges of the jewel when the body portion is closed by the lid, and a spring latch for holding the lid in closed position on the body.

3. A locket comprising a body portion, a lid slideable edgewise in the body portion to close the same, means on the lid for engaging opposite edges of a jewel, and means integral with the body portion for overlapping intermediate edges of the jewel.

4. A locket comprising a body portion, a lid slideable edgewise in the body portion to close the same, means on the lid for engaging

opposite edges of a jewel, means integral with the body portion for overlapping intermediate edges of the jewel, and means for latching the lid in closed position.

5. A locket comprising a body portion, and 70 a lid therefor, the body portion being formed with undercut lips to slidably engage opposite edges of the lid, the lid being formed with undercut lips at intermediate edges thereof to provide sliding engagement for a 75 jewel, the lips on the body portion being adapted to overlap the jewel.

6. A locket comprising a body, and a lid 80 slideable on the body to close the same, the lid being formed with undercut lips at opposite ends thereof to slidably engage opposite end edges of a jewel, the body being formed with undercut lips at opposite sides thereof to engage opposite side edges of the lid and of the jewel.

7. A locket comprising a body, a lid slideable on the body to close the same, the lid being formed with undercut lips at opposite ends thereof to slidably engage opposite end edges of a jewel, the body being formed with 90 undercut lips at opposite sides thereof to engage opposite side edges of the lid and of the jewel, and means for securing the lid in closed position on the body.

8. A locket comprising a body, a lid slideable on the body to close the same; the lid being formed with undercut lips at opposite ends thereof to slidably engage opposite ends of a jewel, the body being formed with undercut lips at opposite sides thereof to engage 100 opposite side edges of the lid and of the jewel, and a spring latch for locking the lid in closed position on the body.

9. A locket comprising a body, a lid slideable on the body to close the same, the lid being formed with undercut lips at opposite ends thereof to slidably engage opposite end edges of a jewel, the body being formed with undercut lips at opposite sides thereof to engage opposite side edges of the lid and of the jewel, and a spring latch for locking the lid in closed position on the body, the latch being concealed within the body when the lid is closed, a thumb piece on the end of the latch and exterior to the body, the latter being 110 formed with a recess to receive the thumb piece whereby the outer face of the thumb piece will lie flush with the outer face of said body.

10. A locket comprising a body, a lid slideable on the body to close the same, the lid being formed with undercut lips at opposite ends thereof to slidably engage opposite end edges of a jewel, the body being formed with undercut lips at opposite sides thereof to engage opposite side edges of the lid and of the jewel, a spring latch secured at one end to the under face of the lid and having a shoulder near its free end adapted to engage the inside of an end wall of the body when the 120

lid is closed, a thumb piece at the free end of the clip and adapted to engage the outer side of said end wall when the lid is closed, the locket being formed exteriorly with a recess in which the thumb piece may be seated whereby the outer face of the thumb piece will lie flush with the outer face of the locket.

In testimony whereof, I have signed this specification.

FRANK KESSLER.
